UNITED STATES PATENT OFFICE.

HJALMAR NILSSON, OF HAMMOND, INDIANA, ASSIGNEE, BY MESNE ASSIGNMENTS,
TO CONTINENTAL TRANSPORT COMPANY, OF CHICAGO, ILLINOIS.

SLED.

1,405,858.

Specification of Letters Patent. Patented Feb. 7, 1922.

Application filed January 7, 1921. Serial No. 435,694.

To all whom it may concern:

Be it known that I, HJALMAR NILSSON, a citizen of the United States, residing at Hammond, in the county of Lake and State 5 of Indiana, have invented certain new and useful Improvements in Sleds, of which the following is a specification, reference being had therein to the accompanying drawings.

This invention relates to sleds, and has for 10 its object the construction of a simple and efficient child's sled which can be easily guided or steered.

Another object of the invention is the production of a child's or hand sled which is 15 comparatively simple in construction and which can be easily steered by the operator standing upon the runners of the sled and slightly turning or exercising the twisting action upon the handle.

20 With these and other objects in view, my invention comprises certain novel combinations, constructions and arrangements of parts as will be hereinafter described, illustrated in the accompanying drawings, and 25 more particularly pointed out in the appended claims.

In the drawings:

Figure 1 is a view in side elevation of a sled constructed in accordance with the 30 present invention, the dotted lines showing the positions of the parts when the sled is in a folded or knocked down condition.

Figure 2 is a longitudinal, sectional view 35 of my sled, taken on the line 2—2 of Fig. 3, looking in the direction of the arrows.

Figure 3 is a top, plan view of the sled.

Figure 4 is a rear view in elevation of the sled.

Figure 5 is a sectional view, taken on line 40 5—5, Fig. 3, and looking in the direction of the arrows.

Figure 6 is an inverted, perspective view of the spring foot rest device.

Referring to the drawings by numerals, 45 1—1 designates two spring steel runners which are extended upwardly at their front ends and are connected by a rod 2, upon which is positioned a sectional tubing 3. Nuts 4 fasten the runners 1 and the sectional 50 tubing 3 upon the rod 2.

Uprights 5 rest at their lower ends upon the runners 1, and each upright is provided with a pair of metal strips 6, which strips 6 are fastened at their lower ends to the sides

of the runners, and their upper ends are 55 fastened to the sides of the uprights 5, securing the uprights to the runners. These strips 6 serve to brace and securely fasten the uprights to the runners. A handle 7 is attached to the upper ends of the uprights, 60 and this handle is provided with grip portions 8. A cross piece 9 is connected at its ends to the uprights 5. Reach beams 10 are connected at their inner ends to the cross piece 9, and by means of strap irons 11 the 65 outer ends of the reach beams 10 are fastened to the sectional tubing 3 between the outer ends of the runners 1. A pair of angles braces 12 are fastened to the cross piece 9 and the uprights 5, and a second pair 70 12^a of said braces are fastened (Figs. 1 and 2) to the uprights 5 and the reach beams 10, producing a very rigid and stable structure, whereby, when the operator exerts a 75 comparatively slight twisting or turning strain upon the grips 8 of handle 7, movement of the forward ends of the spring steel runners will be sufficient to turn or guide the sled in the desired direction.

A seat 13 is secured upon the reach beams 80 10 near the uprights 5.

Spring foot-rest devices 14 are fastened upon the runners 1 contiguous to the uprights 5. Each foot device comprises a twisted body 15 having integral, substantially U-shaped yokes 16 at its ends; these yokes 16 straddle the top of the runners, and suitable fastening means pass through the yokes and the runners for fastening the foot devices to said runners. The twisted bodies 90 15 are formed from single strands of rather heavy metal and are twisted in oppositely extending semi-circular portions so as to provide a broad supporting surface. The operator may stand upon these foot devices, 95 and by reason of their peculiar construction no snow or ice can collect thereon. Further, by reason of the twisted body structure 15, the foot-rest devices constitute a bracing structure for the runners as they lend stability to said runners, since the runners may be accidentally twisted in the rear of the uprights 5, but the foot-rest devices will quickly return the runners 1 to their 100 normal parallel position.

105 In Fig. 1, it will be seen that by removing the ordinary fastening means, such as rivets and bolts for the several parts, that

the parts may be separated sufficiently to allow the sled to be folded or placed in a knocked down condition, as shown.

While I have described the preferred embodiment of my invention, and have illustrated the same in the accompanying drawings, certain minor changes or alterations may appear to one skilled in the art to which this invention relates, during the extensive manufacture of the same and I, therefore, reserve the right to make such alterations or changes as shall fairly fall within the scope of the appended claims.

What I claim is:

1. In a sled, the combination with runners and a handle structure, of foot-rest devices on said runners contiguous to said han-

dle structure, each foot-rest device including a flat open body work resting upon a runner and yokes at the ends of said body work fitting over the runner, and means fastening the yokes and runners together.

2. In a sled, the combination with runners, a handle structure on said runners, of spring foot-rest devices on said runners contiguous to said handle structure, each foot-rest device comprising a twisted body provided at its ends with substantially U-shaped yokes, and means extending through said yokes and runners securing the yokes and runners together.

In testimony whereof I hereunto affix my signature.

HJALMAR NILSSON.
